IMPROVED FILING MACHINE.

A. G. BURTON AND H. W. COVERT, OF ROCHESTER, NEW YORK.

Letters Patent No. 59,741, dated November 20, 1866.

SPECIFICATION.

TO ALL WHOM IT MAY CONCERN:

Be it known, that we, A. G. BURTON and H. W. COVERT, of Rochester, in the county of Monroe, and State of New York, have invented certain new and useful improvements in filing machines; and we do hereby declare that the following is a full and exact description thereof, reference being had to the accompanying drawings making part of this specification—

Fig. 1 is a plan of our improved machine.

Fig. 2, a side elevation.

Fig. 3, a perspective view of one of the ball and socket joints, with the end of the frame on which it rests.

Fig. 4, a perspective view of the top of the reciprocating carriage, with a file attached thereto.

Fig. 5, a bottom view of one end of the adjusting table.

Like letters of reference indicate corresponding parts in all the figures.

It is the object of our improvement to produce a machine that shall be adapted to the general purpose of filing, by the application of power, thereby obviating, in a great degree, the laborious hard work now necessary especially where heavy work is to be dispatched.

As represented in the drawings, A indicates a frame of suitable construction, having longitudinal slots, *a* or equivalent, in the ends, for the connection and adjustment of the carriage frame B, and the sustaining tab or equivalent general support, C, for the reception of the articles to be filed. In order to connect these parts we prefer to use ball and socket joints, of substantially the following construction:

The socket D is made of two parts *b b*, which receive the ball E, and clamp together to hold it fixedly in any position, by means of flanges *c c*, having tightening screws *d d*. The socket is also provided with a base flange *f*, connecting with the slots *a*, by means of a nut and bolt *g*, or equivalent, by which means it is adjustable forward or back.

The carriage frame and table or support are respectively secured to the tops of the balls E E, as shown in fig. 2.

The carriage frame consists simply of a horizontal flange *h*, for attaching to the top of the ball, an uprigbed or back *i*, and lugs *k k*, on opposite sides, for holding the carriage in place and allowing its reciprocation.

To the top of the carriage frame is secured a shaft G, with which are connected a pulley *l*, to receive a belt for applying power to the machine, and a cam *m*, substantially of the form indicated in fig. 2, for acting on the carriage to produce its reciprocations. Any equivalent means of producing the reciprocations of the carriage—such, for instance, as a pitman and crank—may be employed; but we prefer the cam for reasons hereinafter set forth.

The carriage is substantially of the form indicated in figs. 2 and 4, having a body H, which rests against the back of the frame, and flanges *n n*, that run in the lugs *k k*, to hold the carriage in place. Where the cam *m* is employed, we prefer to employ a friction wheel *o*, on top. The sides of the carriage are provided with vertical grooves *p p*, or equivalent, to receive tongues *q q* of clamps I I, which hold the file K in place by means of set screws *r r*. These clamps may be adjusted higher or lower at pleasure.

The side of the carriage is provided with a pin or stop *s*, fitting in any one of a set of adjusting holes. This pin or stop, striking a shoulder *k*, of the frame, will gauge the length of the stroke of the carriage. The reaction of the carriage against the driving cam, when the latter is used, may be produced by any suitable spring arrangement. By this mode of driving the file, nearly all the time is employed in moving it forward or downward to perform its work, while its return movement occupies scarcely any of the time. Thus either time or power, or both, are economized, as may be desired.

The table or support C, as shown, is a simple leaf fastened securely to the ball. Any equivalent form will furnish a general support for the articles to be filed. At each end, on the inside, is an auxiliary leaf L, projecting and adjustable inward toward the file by means of a bearing, M, resting under the main leaf, provided with a transverse slot *v*, running over a set screw *w*.

It is common in saw filing machines to give the file a reciprocating movement, and to perform the required action without particular manipulation; but such arrangements are for a particular use, and are not adapted to the general and promiscuous business of filing. It is our special design to apply power to the purpose, and to make the machine capable of performing many different offices.

To this end the file carriage is made to reciprocate rapidly, and the article to be filed is presented to it on the table or support C. It will be seen that either the carriage or table, or both, are made to adjust nearer together or further apart by means of the flanges f, bolts g, and slots a; and are also made to incline longitudinally or laterally, or to simply turn to any angle, horizontally, by means of the ball and socket joints, as indicated by red lines, fig. 2. This adapts the machine to almost a universal use. Thus, any angle, bevel, or inclination may be given to the edge of the article being filed, or any notch may be made in the same, as the necessities of the case may require.

In addition to this, the auxiliary leaves L L are made adjustable in and out, as indicated in red lines, fig. 1, thus enabling the articles placed thereon to be brought in contact with the edge of the file.

The clamps I and screws r not only enable the file to be readily attached and detached, but also to be adjusted higher or lower at pleasure, as indicated by red lines, fig. 2.

The machine above described is adapted to accomplish much of the filing done in large manufactories and shops, where the same is simply plain work; and, as it is accomplished by the application of power, a great saving in labor and expense is effected. In these respects it differs from saw filing machines or any other for the purpose of filing that we have ever seen.

We do not claim a reciprocating file, nor clamp holder, when they are adjustable, either or both, to specially required positions, as in saw filing machines; but

1. What we claim as our invention, and desire to secure by Letters Patent, is the table C, adjustable in the manner described, in combination with the reciprocating file K, substantially as and for the purpose herein specified.

2. The combination of two ball and socket joints E D, adjustable in position, one bearing a file carriage and the other a table, or support, for the articles filed, for the purpose herein set forth.

3. The combination of the lateral auxiliary leaves L, with the table C, and file carriage H, for the purpose of presenting the article to be filed to the edge of the file, substantially as specified.

4. The arrangement of the machine as a whole, consisting of the carriage frame B, the file carriage H, the table C, provided with the lateral leaves L, and the universal joints D E, constructed as described, the whole operating substantially as herein set forth.

5. The combination of the cam m with the file carriage H, which is provided with a reacting force, so that its returns will economize time and power, as set forth.
